RAILROAD CROSSING SIGNAL

Oscar T. Gregory, Mobile, Ala., assignor to The
Auto Flagger Corporation, Atlanta, Ga.

Application May 19, 1936, Serial No. 80,641

1 Claim. (Cl. 246—128)

This invention relates to railroad crossing signals of the automatic train controlled type and has for the primary object the provision of a device of this character which will display at a crossing on the approach of a train thereto, a signal in the form of a flag, bearing display warning characters clearly observable from a maximum distance and also a signal light in conjunction therewith and will conceal the flag and extinguish the light after the passing of the crossing by the train.

Another object of the invention is the provision of a device of the above stated character which will be inexpensive to manufacture and to install and may be located at any place most convenient with respect to the crossing, and is so constructed that practically the entire device is located above ground and efficiently protected against weather elements.

A further object of this invention is the provision of means for mounting the flag so that it may be folded and hidden from view and protected when the crossing is safe for the passing of traffic and to unfold the flag to extend within a desired distance of the roadbed of the crossing by the approach of a train within a selected distance of said crossing, so that the flag will be positioned well within the line of vision of the drivers of vehicles approaching the crossing and if contacted accidentally by a vehicle will not injure the latter or become damaged itself due to its construction and mounting therefor.

A still further object of this invention is the provision of a combined electrical and mechanical mechanism for the automatic actuation of the signals and which is entirely controlled by a train when approaching within a predetermined distance of the crossing and passing said crossing.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a signal constructed in accordance with my invention and showing the same associated with a railroad crossing and occupying a signaling position.

Figure 2 is a view similar to Figure 1 showing the device when in non-signaling position.

Figure 3 is a fragmentary top plan view illustrating the combined mechanical and electrical

means for actuating the signals and having the cover for said mechanism removed.

Figure 4 is a fragmentary vertical sectional view illustrating the same as that shown in Figure 3.

Figure 5 is a side elevation illustrating a reversing switch for an electric motor employed for the actuation of the signals.

Figure 6 is a sectional view taken on the line 6—6 of Figure 5.

Figure 7 is an end elevation illustrating a main control switch.

Figure 8 is a sectional view taken on the line 8—8 of Figure 7.

Figure 9 is a transverse sectional view showing 15 the mounting for the flag type signal and taken on the line 9—9 of Figure 10.

Figure 10 is a sectional view taken on the line 10—10 of Figure 9.

Figure 11 is a fragmentary front elevation illustrating a portion of the flag.

Figure 12 is a sectional view taken on the line 12—12 of Figure 11.

Figure 13 is a sectional view taken on the line 13—13 of Figure 11.

Figure 14 is a diagrammatical view illustrating 25 the wiring diagram.

Referring in detail to the drawings, the numeral 1 indicates a railroad crossing, the track being indicated by the character 2 and the train by the character 3. A signal device 4 forming the subject matter of the present invention is located adjacent the crossing 1 which, when in signaling position, will provide an effective warning to traffic approaching the crossing and will be clearly observable for a maximum distance from the crossing. The signaling device includes signals 5 and 6, the signal 5 being in the form of an electric lamp in rear of a lens of a desired color while the signal 6 is in the form of a flag constructed from any desirable material, preferably a fabric on which is applied a series of angularly related markings 7. These markings are of a distinguishable color so that they may be observed for a maximum distance from the crossing. The flag 6 also has applied thereto characters spelling the words "stop-train-in". The characters are of an easily distinguishable color and secured to the flag within the characters are jewels 8 capable of reflecting light rays at night 40 time so that the words can be easily read in the dark by the headlamp rays of light of a motor vehicle shining thereon. The characters may have a background of a different color from the other markings on the flag such as red to indi- 55

cate danger. Rows of grommets or eyelets 9 are secured to the flag 6 and have laced therethrough flexible supporting elements 10 each having one end secured to the flag adjacent the 5 free end of the latter. Reinforcing strips 11 are secured to the fabric of the flag where the eyelets pass through the fabric and these reinforcing elements are of the type to cause the fabric of the flag to fold when the lower edge of the 10 flag is drawn upwardly in the direction of the upper edge.

The signals 5 and 6 are carried by a supporting structure 12 which includes a vertically arranged hollow post 13 supported by a suitable foundation 15 14 and a platform 15 mounted on the upper end of the post and to which is secured a horizontally arranged casing 16 adapted to extend across the roadway at a desired height from the ground. The signal 5 is mounted on the post 13 and the 20 signal 6 is movable into and out of the casing 16 so that when the signal 6 is in a signaling position it will be arranged transversely of the roadway of the crossing in a depending position with the lower edge terminating approximately the 25 height of a motor vehicle hood so that the signal 6 will be in alignment with the vision of the driver of the motor vehicle and also in a position so that the light rays of the headlamps of the motor vehicle will strike the flag and jewels thereon, 30 rendering the characters clearly readable, as well as the other markings, at night time. The markings and characters being of distinguishable colors may be easily read in the day time.

The casing 16 is of substantially U-shape in cross section so that the flag may readily move into and out of the casing and when confined in the casing will be protected against weather elements. A partition 17 is arranged in the casing to which the upper edge of the flag is secured and 40 forms a stop for the flag to fold against when moved upwardly in the casing. The partition 17 is apertured to permit the flexible elements 10 to extend therethrough and they also extend through slots 18 formed in the top of the casing. 45 A pair of pulleys 19 are journaled on the casing and have trained thereover a pair of flexible elements 10, while a third of the flexible elements 10 is trained over pulleys 20 and secured to one of the flexible elements of said pair of flexible 50 elements, as shown at 21. The pulleys 20 are journaled on the casing. The flexible elements after passing over the pulleys extend through a vertical wall 22 of the platform 15 and over guide pulleys 23 carried by said vertical wall 22. The 55 flexible elements after passing over the pulleys 23 are wound on and secured to drums 24 and the latter are secured to an operating shaft 25. The operating shaft is rotatably mounted in supports 26 mounted on the platform 15. A removable hood 27 overlies the pulleys 19 and 20 and the flexible elements after they leave the casing and pass to the drums. The hood 27 is hinged to the casing, as shown at 28, and is equipped with a catch 29 to prevent the hood from accidentally swinging into an open position. The 65 hood when in closed position contacts the casing and a flange on the vertical wall 22 of the platform so as to exclude weather elements from the interior of the hood thereby protecting the flexible elements and pulleys. A removable cover 29' 70 is carried by the platform 15 to protect the mechanism supported by said platform from weather elements and from being tampered with. A suitable locking mechanism (not shown) may be provided for securing the cover 29' in place on the 75

platform. The casing 16 besides being secured at one end to the vertical wall of the platform has its opposite end connected to said vertical wall by supporting rods 30.

A combined electrical and mechanical means 5 31 is supported by the platform and operatively connected to the shaft 23 for rotating the latter in opposite directions for the purpose of folding and unfolding the flag. The mechanism 31 includes a reversible electric motor 32, the shaft 10 thereof being connected to a stub shaft 33 by a coupling 34. The stub shaft 33 is journaled in the support 35 mounted on the platform and has secured thereto a worm 36 which meshes with a worm gear 37 secured to the shaft 25. 15 The shaft 25 also has secured thereto a beveled gear 38 meshing with a beveled gear 39 secured to a feed shaft 40. The feed shaft 40 has the usual feed threads thereon to be engaged by a feed nut 41. The feed shaft 40 is rotatably supported by standards 42 mounted on the platform. The standards also slidably support a shaft 43 which parallels the feed shaft and has secured thereto stop collars 44 between which operates the feed nut and the latter also contacts said 20 collars for shifting the shaft 43 in opposite directions as the feed nut travels in opposite directions on the feed shaft 40. The feed nut is slidably secured to the shaft 43 so that the feed nut will not follow the rotation of the feed shaft but 30 which will travel endwise of said feed shaft. An arm 45 is secured to one end of the shaft 43 and has pivoted thereto a link 46. The link 46 is pivoted to an actuating arm 47 mounted on a shaft 48. Journaled on the shaft 48 is a sleeve 35 49 and the sleeve is rotatably supported by a bracket 50 secured to the platform 15. The shaft 48 is free to turn in the sleeve 49. A trip plate 51 is secured to the sleeve adjacent the actuating arm 47 and includes diverging arm portions 52 40 between which operates a pin 53 secured to the trip arm 47. A coil spring 54 has one end secured to the trip arm 47 adjacent the latter's free end and the other end of said spring is secured to the platform. The purpose of the spring 54 45 is to cause the trip arm to snap past dead center position when moving in either direction. The movement of the arm 47 is transmitted to the trip plate by the pin 53 contacting either of the arm portions 52. The purpose of the trip plate 50 is to actuate a reversing switch 55, the latter being electrically connected in an electric circuit and in which is also connected the electric motor so that the latter will be reversed for the purpose of folding and unfolding the flag. The reversing 55 switch 55 includes a support 56 of insulating material mounted on the platform to which are secured contacts 57, 58, 59 and 60. The switch 55 also includes a movable element 61 constructed of insulating material and is secured to the sleeve 60 49. Mounted on the movable element 61 of the switch 55 are contacts 62 and 63. The movable element 61 of the switch 55 has two positions and when in one position the contacts 62 and 63 engage the contacts 57 and 58 and when in the other or second position, the contacts 62 and 63 engage the contacts 59 and 60. The movable element 61 of the switch 55 is temporarily retained in either of its positions by a spring element 64 engaging in notches 65.

An arm 66 is secured to the sleeve 49 and pivoted to said arm is a connecting link 67. The connecting link 67 connects with a main control switch 68 mounted on the platform. The main control switch 68 is of the electrically actuated 75

type, that is, the movable contact 69 thereof may be attracted by an electromagnet 70 when energized. The movable contact 69 is hingedly supported, as at 71, and depends between spaced contacts 72 and 73, integrally connected with each other as well as electrically and are slidably supported by a block 74 of insulating material. A weight 75 is secured to the movable contact 69 for returning the latter to a perpendicular position 10 when freed from either of its positions of engaging the contacts 72 or 73. The block 74 is mounted in guides 76 carried by the platform 15 and pivoted to the block is a link 77 and the latter is pivoted to a lever 78 adjacent the pivoted end of the latter. The lever 78 is pivoted, as shown at 79, to a support 80 forming a part of the main switch. The support 80 has the movable contact 69 hinged thereto. The other end of the lever 78 has the connecting rod 67 pivoted thereto. Opposing the movable contact 69 is a stop 81 which is secured to the lever 78. The electromagnet 70 has connected thereto electrical conductors 82 and 83, the electrical conductor 82 being connected to an electrical source 84. The electrical source 84 is connected to one of the rails of the train track 2 by a conductor 85 while the other rail of the track has the conductor 83 connected thereto. The conductor 85 is connected to its respective rail of the track a selected distance from one side of the crossing 1 while the conductor 83 is connected to its respective rail a selected distance from the opposite side of the crossing 1 so as to create an electrical block system which extends for a selected distance from one side of the crossing to a selected distance from the other side of the crossing so that when a train is within the block the electromagnet will be energized. Electrical feed lines 86 and 87 are connected to an electrical transformer 88 and connected to the latter are conductors 89 and 90. The conductor 89 is connected to the movable contact 69 of the main control switch 68 and the conductor 90 is connected to the contact 60 of the reversing switch 55. A conductor 91 is connected to the contact 59 of the switch 55 and to the contacts 72 and 73 of the main control switch. A conductor 92 connects the contact 58 of the reversing switch to the conductor 91 and the conductor 93 connects the contact 57 of the reversing switch to the conductor 90. Conductors 94 and 95 are connected to the electric motor 32 and to the contacts 62 and 63 of the reversing switch 55.

The signal 5 is connected in an electric circuit (not shown) and also in this circuit is connected a control switch 96 mounted on the platform 15 and includes spaced contacts 97 adapted to be bridged by a pivotally mounted bridging element 98 forming an integral part of an arm 99. One end of a coil spring 100 is connected to the arm 99 and the other end of said spring is connected to one end of a pivotally mounted lever 101. The opposite end of the lever is forked, as shown at 102 to receive a pin 103 secured to the feed nut 41. When the feed nut 41 arrives at the end of its movement in one direction it imparts pivotal movement to the lever 101 causing the element 98 to bridge the contacts 97 and complete the electric circuit to the signal 5 and when the nut 41 reaches the limit of its movement in an opposite direction pivots the lever 101 in an opposite direction swinging the element 98 out of engagement with the contacts 97 interrupting the circuit to the signal 5.

The flag when in folded position or occupying

a position within the casing 16, the various parts of the combined electrical and mechanical mechanism 31 occupy positions, as shown in Figure 4. A train entering the block energizes the magnet 70 and the latter attracts the movable contact element 69 engaging the latter with the contacts 72 completing the electric circuit to the motor 32 through the reversing switch 55 to cause rotation of the electric motor in a direction for driving the drums 24 in a direction to unfold 10 the flag or permit the latter to gravitate outwardly of the casing and assume signaling position, as shown in Figure 1. The electric motor drives the feed shaft 40 causing the nut 41 to travel to the right in Figure 4, actuating the switch 96 to complete the circuit to the electric signal 5. As the nut 41 travels to the right in Figure 4 it engages one of the collars 44 causing an endwise movement of the shaft 43 to the right in Figure 4. This movement of the shaft 43 im- 20 parts pivotal movement to the trip arm 47 to the right in Figure 4. The movement of the trip arm 47 is synchronized with the shaft 43 until the trip arm 47 reaches a position slightly past dead center position and the spring 54 then acts to 25 snap the trip arm rapidly to the right in Figure 3, carrying therewith the trip plate 51 imparting rotation to the sleeve 49. The sleeve 49 swings the movable element 61 of the reversing switch 55 to the right in Figure 4 and at the same time the 30 lever 78 is rocked on its pivot to shift the position of the link 77 to move the contact 72 away from the contact 69 interrupting the circuit to the electric motor 32, consequently stopping the lowering or unfolding of the signal 6. The electromagnet 35 70 remains energized as long as the train is in the block, maintaining the contact 69 of the switch 68 to the right in Figure 4. However, when the train leaves the block the magnet 70 is deenergized and the weight 75 acts to move the contact 40 69 into a perpendicular position and into engagement with the contact 73 completing the electric circuit to the motor 32. However, the reversing switch having had the element 61 thereof shifted to the right in Figure 4, brings about reverse 45 operation of the electric motor to elevate or fold the signal 6 into the casing 16. The reverse operation of the electric motor causes the nut 41 to travel in an opposite direction and this movement of the nut engages the left hand collar 44 in 50 Figure 4 and moves the shaft 43 to the left in Figure 4. The movement of the shaft 43 to the left in Figure 3 imparts a corresponding movement to the trip arm 47 and as the latter passes dead center position the spring 54 acts to rapidly 55 complete the movement of the trip arm to the left in Figure 3, so that the trip plate 51 will be thrown to the left repositioning the element 61 of the reversing switch 55 to the left in Figure 4 and at the same time the block 74 is shifted to 60 the left drawing the contact 73 away from the contact 69 interrupting the circuit to the electric motor stopping the operation of the motor as the signal 6 is completely folded within the casing. Therefore, it will be seen that all parts of the 65 mechanism 31 have been returned to their initial position ready for operation for lowering or unfolding the signal 6 as soon as the next train enters the block. The movement of the feed nut 41 to the left in Figure 3 brings about a pivotal 70 movement of the lever 101 so as to disengage the bridging element 98 and the contacts 97 after the train has left the block for interrupting the circuit to the electric signal 5. The stop 81 on the lever 78 prevents the movable contact element 69 of 75

the main switch 68 from following the contact 73 when the latter is moved away from said contact 69 so as to assure said contact 69 assuming a perpendicular position when the various parts 5 of the mechanism have been restored to their initial position and after the folding of the signal 6.

Having described the invention, I claim:

A device for operating a railroad crossing signal 10 comprising a supporting means, a shaft carried by said means for rotation in opposite directions to move a signal into signaling and non-signaling positions, a reversible electric motor carried by the supporting means and connected to said shaft, 15 a feed shaft driven by said first shaft, a sliding shaft carried by said supporting means, spaced collars secured to the sliding shaft, a feed nut

meshing with the feed shaft and slidable on the sliding shaft between the collars, a reversing switch carried by the supporting means, a train controlled electric circuit connected to the reversing switch and to the electric motor, a main 5 control switch connected to the circuit and including a hingedly mounted and weighted movable contact and slidable spaced contacts and having the contacts thereof connected in the circuit, a trip mechanism actuated by the movement 10 of the sliding shaft to operate the reversing switch and the movable contacts for the main switch, and an electromagnet connected in the electric circuit for the actuation of the weighted movable contact of the main switch. 15

OSCAR T. GREGORY.
